UNITED STATES PATENT OFFICE.

HENRY J. PLANT, OF ROCHESTER, NEW YORK, ASSIGNOR TO DEFIANCE CHECK WRITER CORPORATION, OF ROCHESTER, NEW YORK, A CORPORATION OF NEW YORK.

PRINTING-MACHINE.

1,352,690.

Specification of Letters Patent. Patented Sept. 14, 1920.

Application filed March 8, 1916, Serial No. 32,810. Renewed March 12, 1920. Serial No. 365,331.

To all whom it may concern:

Be it known that I, HENRY J. PLANT, a citizen of the United States, and resident of Rochester, in the county of Monroe and State of New York, have invented certain new and useful Improvements in Printing-Machines, of which the following is a specification.

The present invention relates to printing machines and more particularly to the type known as check writing machines and check protectors. An object of the invention is to construct a machine which may be used for writing in checks different amounts, each of which bears a certain ratio to the par value of shares of stocks, bonds or the like, the number of shares being determined by suitable indicating means and type, that represents the amount to be written, being shifted to printing position upon the selection of the number of the shares on the indicating means, provision being made whereby these amounts may be changed to correspond with the interest to be paid on the shares. Another object of the invention is to provide a mounting for the printing member whereby the latter may be readily and quickly detached from its supporting drum. Still another object of the invention is to provide a centering means which may be adjusted by the user of the machine to shift the printing line slightly in either direction for the purpose of obtaining proper coöperation between the line of type and the platen. A further object of the invention is to provide an improved means of connecting the platen to its supporting member in such a way that the platen may be readily and quickly detached, the securing means being of simple construction and not liable to get out of order.

To these and other ends, the invention consists of certain parts and combinations of parts all of which will be hereinafter described, the novel features being pointed out in the appended claims.

In the drawings:—

Figure 1 is a vertical section through the machine in a direction transverse of the axis of the rotary printing member;

Fig. 2 is a longitudinal vertical section through the machine;

Figs. 3 and 4 are detail views of portions of the centering means;

Fig. 5 is a perspective view of one section of the printing member; 55

Fig. 6 is a detail sectional view of the platen and its mounting; and

Fig. 7 is a development of portions of the printing member and the dial. 60

Referring more particularly to the drawings, 1 indicates the base or bed plate to which a casing 2 is pivoted or hinged at 3, the top wall 4 of the casing serving as a table or a work support and having a slot 5 65 through which the work is pressed into co-operation with the printing mechanism.

The printing mechanism preferably embodies a shaft 6 journaled at 7 in opposite side walls of the casing 2 and having two 70 drum sections 8 and 9 mounted thereon. The drum section 8 is rigidly secured to the shaft 6 by a pin 10 while the drum section 9 is guided for movement longitudinally of the shaft 6 by means of a pin 11 operating 75 in slots 12 in the hub of the section 9. A spring 13 is arranged between the hubs of the two drum sections and tends normally to press the section 9 away from the section 8. Also arranged on the shaft 6 are two 80 nuts 14 one of which acts as lock nut for the latter and both of which serve to hold the drum section 9 toward the section 8 against the action of the spring 13.

Surrounding the sectional drum is the 85 printing member which is preferably of cylindrical form and divided into two semi-circular sections 15, the abutting edges of which are notched at 16 in order to receive pins 17 between them, the pins projecting 90 from cylindrical surfaces 18 on the drum sections 8 and 9 and serving to define the positions of the printing sections with relation to the indicating means to be described. The opposite edges of the printing 95 member may also be beveled as at 19 in order to be received beneath undercut shoulders 20 on the drum sections 8 and 9, the nuts 14, when turned in one direction, serving to press the member 9 toward the 100

member 8 and force the opposite edges of the printing member sections 15 under the shoulders 20, and when turned in the other direction, releasing the printing member 5 and permitting its two sections to be removed from the drum.

Also secured to the shaft 6 on an end 21 thereof extended through the casing 2 to the exterior of the latter is a dial wheel 22 10 to which a hand wheel 23 is connected by lateral projections 24. A pointer at 25 on the casing 2 cooperates with the dial wheel 22 to point out the line of type at the printing point.

15 In this embodiment of the invention, the indicator or dial wheel is provided with consecutive numbers from 1 to 100 and these numbers represent shares of stock or bonds. The printing wheel or member is provided with lines of type which will write into a check an amount in words and numerals, bearing a ratio to the par value of the shares of stock. In the illustrated embodiment, this ratio is 2 per cent., so that if 20 the indicating wheel be turned to 3, for three shares of stock, then at the printing point or opening 5 the line of type will be arranged to print in words and numerals "Six dollars" on the check. Of course the 25 par value need not be one hundred dollars, nor need the ratio be 2%, and it is for this reason that the printing cylinder is made removable so that other cylinders may be attached to the drum. This machine is especially adapted for banks and large corporations which are required to make out a 30 large number of checks to pay dividends on their stocks and bonds. It is to be understood, however, that all the improvements 35 herein claimed are not limited to a machine for performing this work.

Another feature of this invention is the centering means which preferably comprises a notched member 26 formed on the drum section 8 and engaged by a yielding device 45 on the casing 2. This yielding device is preferably in the form of a ball 27 carried eccentrically by a rotary support 28 which is externally threaded and engages with an 50 internally threaded opening in the casing 2, being held in its adjusted position by a lock nut 29. The ball is confined at the mouth of the bore in the rotary member 28 and is pressed into said mouth by a plunger 55 30 acted upon by a spring 31, the other end of the bore being closed by a plug 32 which abuts the spring 31 and is adjustable to vary the tension of the spring, a lock nut 33 holding the plug 32 in its adjusted position. 60 By this arrangement a relative adjustment between the notched device and the yielding device may be secured in order to effect a slight shifting of the centering position to obtain proper coöperation between the 65 platen and the line of type.

For coöperation with the printing member, there is provided a platen 34, formed of rubber or other material and firmly held within a sheath 35 which partially incloses the rubber and is formed of thin sheet metal. 70 The sheath is received within a groove of a supporting member 36 and is held within the groove by interlocking devices comprising a headed lug 37 arranged within the groove at one end of the latter and engaged 75 by the sheath, the latter for this purpose having a slot at one end. The other end of the sheath has a projection 39 extending laterally therefrom and externally threaded. This projection operates within a slot 40 on 80 the support 36 and is held within the slot by a clamping nut 41. This clamping device is received within a seat 42 formed in the upper face of the platen support 36 so as to prevent longitudinal movement of the platen 85 and its sheath within the groove of the support 36. To remove the platen, the clamping nut 41 is turned until it passes above the top of the recess 42, after which the platen and its sheath may be shifted laterally to 90 disengage the sheath from the headed projection 37 and the projection 39 from the support 36.

Any suitable means may be employed for mounting the platen support 36 so that coöperation may be established between the printing member and the platen 34. In this instance, the platen support 36 is provided with a stem 43 which is guided in a block 44, the block having a pocket 45 about the 100 stem in which is received a helical spring 46, the latter abutting the bottom of the pocket and the head or enlargement 47 on the stem 43. The block 44 may be supported by a bridge 48 which is sustained in 105 spaced relation from the table 4 by uprights 49. Operation of the platen is effected by a lever 50 pivoted at 51 to the block 44 and coöperating with the upper end or head 47 of the platen stem 43.

An inking roller 53 coöperates with the printing member and is supported in a housing 54 which is adjustably secured to the casing 2 by a means which does not form any part of the present invention. Projections 115 55 and 56 are extended rearwardly from the casing 2 to support the latter when it is thrown rearwardly on its hinge 3. A latch 57 secures the casing 2 to the base 1.

The operation of the invention is as follows: The hand wheel 23 is turned producing a movement of the dial 22 and of the type cylinder, bringing the desired line of type beneath the slot 5. The check is presented face down over the slot in the proper 120 position, after which the handle or lever 50 is depressed, carrying the platen 34 downwardly to press the check through the slot 5 against the type wheel.

According to the present invention, it is 130

possible to write quickly and accurately checks for the payment of dividends on stocks and bonds for any number of shares within the range of the machine. The type 5 member is removable and other members may be substituted therefor to correspond with the rate of dividend to be paid. The securing means for the type member is easily operated and is simple in construction. The centering means gives an adjustment which enables the proper coöperation between the platen and the line of type to be obtained. The platen is secured by a means which facilitates the removal and attachment of the same.

What I claim as my invention and desire to secure by Letters Patent is:

1. In a printing machine, indicating means having consecutive numbers thereon, 20 a printing member having lines of type thereon, each line being adapted to print an amount which bears a definite relation to one of the numbers on the indicating means, and means detachably securing the printing 25 member in proper relation to the indicating means so that other printing members bearing other relations may be associated with said indicating means.

2. In a printing machine, a suitably 30 mounted shaft, indicating means connected to the shaft, a pair of relatively adjustable heads mounted on said shaft, a spring tending to separate said heads, means for holding said heads against separation, means for 35 preventing the relative turning of the heads, a cylindrical printing member detachably interlocked with said heads, and means for defining the position of the printing member on the heads to correspond with the indicating means.

3. In a printing machine, a suitably 40 mounted shaft indicating means connected to the shaft, a pair of heads mounted on said shaft to turn therewith but to move 45 relatively in an axial direction, said heads having undercut portions, a printing member of cylindrical form engaged at opposite edges by said heads and divided longitudinally into sections abutting at both sides, 50 and means for defining the position of the printing member on the heads to correspond with the indicating means.

4. In a printing machine, a suitably 55 mounted shaft, a pair of heads mounted on said shaft and each provided with a cylindrical bearing surface, and an undercut portion at one side of the cylindrical bearing portion, one of said heads being rigidly secured to the shaft and the other of said 60 heads being held against turning on the shaft but movable axially thereof, a spring mounted between the heads and tending to separate them, a nut on the shaft tending to hold the heads against separation, and a sectional cylindrical printing member bearing

against the cylindrical portions of the heads and having its opposite edges engaged by the under cut portions on the heads, and means for defining the position of the printing member on the heads to correspond with 70 the indicating means.

5. In combination with a grooved platen support provided with a slot at one end, a sheathed platen having its sheath provided with a slot at one end and a projection at 75 the other end operating in the slot in the platen support, a nut mounted on said projection for engagement with the platen support, and a headed projection at that end of the platen support opposite the slot in the 80 latter, for engagement with the slotted end of the sheath.

6. In combination with a grooved platen support, a sheathed platen received within the groove of said support, interlocking connections between one end of the platen sheath and the support made effective by a movement of the platen and its sheath in the direction of their lengths, and a screw clamp carried by the opposite end of the sheathed 90 platen and adapted to interlock with the platen support after the sheathed platen has been interlocked with the opposite end of the platen support.

7. In combination with a grooved platen 95 support having a slot at one end and a recess in its upper face near one end of the slot, a sheathed platen adapted to interlock with the platen support by a movement in the direction of its length, said sheathed 100 platen carrying a projection arranged to operate in the slot of the platen support, and a clamping nut operating on said projection and adapted to engage in the notch or recess in the platen support for the purpose 105 of locking the sheathed platen to the support.

8. In a printing machine, the combination with a rotary printing-member having a plurality of lines of type thereon, and a platen 110 for coöperation with said lines of type one at a time, of centering means for centering each line in coöperative relation with the platen, said centering means comprising a notched member rotating with said printing member, a movable member coöperating therewith, one of said members being adjustable on the part by which it is carried and in the direction of the rotation of the notched member for the purpose of causing 115 a slight shifting of the centering position in order that proper coöperation between the platen and the printing lines may be obtained.

9. In a printing machine, the combination 125 with a rotary printing member having a plurality of lines of type thereon, and a platen for coöperation with said lines of type, one at a time, of centering means for centering each line in coöperative relation with the 130

- platens, said centering means comprising a rotary notched member turning with the printing member, and a yielding device adjustable laterally in the direction of rotation of the notched member for effecting a slight shifting of the centering position in order that proper coöperation between the platen and the printing lines may be obtained.
10. In a printing machine, the combination with a rotary printing member having a plurality of lines of type thereon, and a platen for coöperation with said lines of type one at a time, of centering means for centering each line of type in coöoperative relation with the platen, said centering means comprising a rotary notched member turning with the printing member, a yielding device for coöperation with the notched member, and a rotary carrier for said yielding device having the latter eccentrically arranged thereon so as to be adjusted later-

ally in the direction of rotation of the notched member for effecting a slight shifting of the centering position in order that a proper coöperation between the platen and the printing lines may be obtained.

11. In a printing machine, the combination with a rotary printing member having a plurality of lines of type thereon, and a platen for coöperation with said lines of type one at a time, of centering means for centering each line in coöoperative relation with the platen, said centering means comprising a rotary notched member turning with the printing member, a spring pressed ball coöoperating with the notched member, and a rotary carrier on which the spring pressed ball is eccentrically mounted for effecting a slight shifting of the centering position in order that proper coöperation between the platen and the printing lines may be obtained.

HENRY J. PLANT.
